(57) **CLAIM**

The ornamental design for an aircraft, as shown and described.

DESCRIPTION

FIG. 1 is a front, left perspective view showing an aircraft according to our design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a rear, left perspective view thereof; and,

FIG. 9 is a front, left perspective view of the aircraft of FIG. 1 shown with propellers in broken lines.

Throughout the Figures, broken lines showing environment or structure are for illustrative purposes only and form no part of the claimed design.
